UNITED STATES PATENT OFFICE.

JOHN STYNSBERG, OF DULUTH, MINNESOTA.

HEATING-STOVE.

1,250,707.

Specification of Letters Patent. Patented Dec. 18, 1917.

Application filed August 23, 1915. Serial No. 46,889.

To all whom it may concern:

Be it known that I, JOHN STYNSBERG, a citizen of the United States, residing at Duluth, in the county of Saint Louis and State of Minnesota, have invented certain new and useful Improvements in Heating-Stoves, of which the following is a specification.

My present invention relates to a new and improved heating stove; and the principal object of the invention is to afford facilities whereby a continuous circulation of air may be brought in contact with the heating surfaces of the stove and distributed throughout the room or the adjacent rooms in an advantageous manner.

Another object of this invention is to provide an improved stove wherein means are provided for controlling the circulation of air about the heating surfaces to the end that the greatest possible efficiency of the stove may be attained at all times.

A further object of this invention resides in the provision of an improved heating stove wherein the cold air from the intake ports is conducted directly through, or rather above the fire box so that when it emerges into the heating dome it will be thoroughly heated, and at which time it may be transmitted about the room or conducted to the adjacent rooms.

A still further object of this invention is to provide a device of the type in question which consists of but few parts whereby, it is believed, that the same may be manufactured at a comparatively low cost.

The above and other objects which will become apparent, are accomplished by such means as are shown in their preferred form in the accompanying drawings, described in the following specification and then more specifically pointed out in the appended claim.

In the accompanying drawings wherein like characters designate like parts throughout the several views;

Figure 1 is a view in front elevation showing my improved heating stove in its preferred embodiment.

Fig. 2 is a similar view illustrating the body portion of the stove with the various ornamental paraphernalia eliminated.

Fig. 3 is a vertical section of the stove body with parts removed.

Fig. 4 is a view in bottom plan illustrat-

ing in detail the air intake ports and the means for controlling the same.

Fig. 5 is a view taken in vertical section showing the outer fire box casing and the pivoted coal chute.

Fig. 6 is a view in top plan showing the fire box.

Fig. 7 is a view in top plan showing the top cover of the stove.

In the accompanying drawings the numeral 10 designates the base structure or ash pit that is supported by a plurality of legs 11 and carries a door 12; the latter being hingedly connected thereto as at 13. The hopper or fire box 14 is fixed to the structure 10 in any desirable manner and in turn supports a heating drum in the form of a dome 15 through the medium of a cylindrical casing 16. This casing 16 is of greater diameter than the fire box and extends laterally beyond it on all sides. In order to receive the ashes falling through the grate 17, the structure 10 is provided with a removable pan 18 which is clearly shown in Fig. 3.

The heating dome 15 is connected by air conducting pipes 19, with intake ports or hoods 20 on the fire box as shown in Fig. 3. These hoods 20 flare toward their lower ends to facilitate the collection of air and its conduction to said pipes 19. As it will be appreciated during the continuance of the following description, it is especially desirable to provide means for controlling the intake of air through the ports 20. To this end the lower portion of the ports are provided with the inturned lips 21 that coöperate with the pivoted dampers 22. It will be understood that when the dampers 22 are in a closed position they will rest on the lips 21. It is also desirable to provide handles such as 23 for properly manipulating the dampers.

The cylindrical casing 16 is provided with a cut-out that is partly closed by a hinged door 24, while a second door 25 in the form of a coal chute is employed to normally close the remaining portion thereof. By reason of the fact that the door 25 carries a pair of sheet metal ears 26 it will be understood that upon moving the same into the position shown in dotted lines in Fig. 5, an efficient coal chute will be formed. It will also be recognized that ears 27 are shown on the door 25 to facilitate the actuation thereof.

The upper portion 28 of the heating dome

is removable so that access may be had to the interior of the stove for the purpose of cleaning, etc. The upper portion 28 is provided with a series of cut-outs 29 that are normally closed by pivoted doors 30 which open at an oblique angle to discharge the heated air laterally into the room. However by properly operating the doors 30 which operate as dampers the air within the heating dome will be allowed to circulate into the room. It is also desirable to eliminate one of the covers 30 in connection with one of the cut-outs 29 and to arrange a collar 32 in connection with the latter. The purpose of this latter construction will be more specifically pointed out hereinafter.

The cover 33 is designed to fit about the upper portion of the heating dome as shown in Fig. 1 and is provided with a series of cut-outs 34 which register with certain of the cut-outs 29. A comparatively larger cut-out 35 is formed in the cover 33 which is adapted to expose the collar 32 which extends about a cut-out 29 consequently a conducting pipe may be engaged with the collar 32 and thus serve to conduct the air from the heating dome to an adjacent room. In the event that the conducting pipe is not in use, a cap (not shown) may be engaged with the cover 33 so as to cover the opening 35 in a convenient manner.

In the accompanying drawings I have shown a smoke pipe 37 having connection with the cylindrical casing 16 below the heating dome.

The fire is generally built upon the grate 17, the smoke accumulating within the cylindrical casing 16 and passing outwardly through the pipe 37. The dampers 22 are now open and as the heated air within the pipes 19 rises, cold air will be drawn in through the ports 20. As the air from the heating dome 15, passes off through the openings 29 and air will be drawn upwardly through the pipes 19 and thus a continuous circulation attained. The hoods 20 on the fire box or pot being arranged to flare downwardly and outwardly and extend around a large area of the outer face of the fire pot will cause the cold air which passes up therethrough to be heated by contact with their inner walls which constitute the outer walls of the fire pot whereby the so heated air will

rise and be superheated in its passage through the pipes 19 so that when it is discharged into the room it will be in a highly heated condition.

From the foregoing it is believed that the advantages and novel features of my invention may be readily understood, and therefore, further detailed description is deemed unnecessary.

In reducing my invention to practice I find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without sacrificing any of the advantages of my invention as defined in the appended claim.

Having thus fully described my invention, what I claim as new and desire to secure by Letters Patent is:

A heating stove including a fire pot, a heat chamber disposed above said pot and communicating therewith and of a diameter greater than that of said pot, a drum mounted on the upper end of said chamber and separated therefrom, outwardly flared downwardly opening hoods mounted on the outer face of said fire pot and shaped to conform to the shape thereof, said hoods being arranged over openings in said heat chamber and forming flared air collecting mouths having a heated inner wall whereby the collected air is heated and caused to rise in said hoods, pipes connected with the upper ends of said hoods and extending through said heat chamber and discharging into said drum, said pipes being completely housed in said chamber and spaced from the side walls thereof, and damper controlled discharge pipes opening from the top of said drum whereby the heated air is directed into the surrounding atmosphere.

In testimony whereof I affix my signature in presence of two witnesses.

JOHN STYNSBERG.
